WALLACE I. STIMPSON AND HARRY A. DAVIS, OF HOPEDALE, MASSACHUSETTS, ASSIGNORS TO DRAPER CORPORATION, OF HOPEDALE, MASSACHUSETTS, A CORPORATION OF MAINE.

SHUTTLE.

Application filed August 24, 1925. Serial No. 51,952.

To all whom it may concern:

Be it known that we, WALLACE I. STIMPSON and HARRY A. DAVIS, citizens of the United States, residing at Hopedale, in the county of Worcester and State of Massachusetts, have invented an Improvement in Shuttles, of which the following description, in connection with the accompanying drawings, is a specification, like characters on the drawings representing like parts.

This invention relates to loom shuttles and more particularly to the bobbin holding end of loom shuttles of the filling replenishing type.

15 It is now the common practice in filling replenishing shuttles to provide bobbin holding jaws for detachable engagement with the filling carrier or bobbin and to associate with the jaws a bobbin guide for 20 guiding the bobbin into position between the jaws.

During replenishment of filling, the incoming filling carrier is utilized to throw out the filling carrier previously in the shuttle, and during this operation much strain is placed upon the parts comprising the bobbin holding end of the shuttle, and such parts frequently become loose or detached, or they may become broken, especially do 30 the spring jaws themselves become broken near the bobbin holding portions, during transfer.

One of the objects of the present invention is to provide improved means for holding the parts at the bobbin holding end of the shuttle in their mutually assembled 35 relation and to thereafter insure permanency of the relation between the parts, that they may not be disturbed during weaving 40 operations.

Heretofore it has been the common practice to provide bobbin holding jaws with a shank portion bent upon itself, but relatively short in length, and to secure the shank 45 portion to the shuttle body by a transverse bolt, and likewise, it has been common heretofore to provide a bobbin guide between the jaws, held to the shuttle by a wood screw. The present invention overcomes the manifest defects of such construction and secures 50 permanency in the relation of parts once they have been properly assembled.

The invention will best be made clear by

the following description and the accompanying drawings of one good form thereof. 55

In the drawings:

Fig. 1 is a perspective view of the bobbin holding end of a shuttle of the filling replenishing type with the parts disassembled;

Fig. 2 is a longitudinal section of the bobbin holding end of the shuttle, showing the parts assembled in accordance with the present invention;

Fig. 3 is a plan view of a shuttle containing the present invention;

Fig. 4 is a longitudinal sectional view of a modification; and

Fig. 5 is a transverse section on the line 5—5 of Fig. 2.

The shuttle comprises the body portion 1 having the usual bobbin chamber 2 and provided at one end with a shank receiving chamber 3. The chamber 3 is cut into the wood of the shuttle and the upper portion 75 thereof is enlarged or widened (as at 4) thereby forming a shelf or shoulder 5 in the shuttle wood at the top of the shank receiving chamber. At the bottom of the shank receiving chamber 5, the body of the shuttle is formed with a cut out portion 6 of a size to receive the bottom plate of the bobbin guide, as will later appear.

The bobbin holder comprises the shank portion 7 which is bent upon itself or rounded at 8, and from the shank portion extend the bobbin holding jaws 9 and 10, each of which may be provided with the usual bobbin holding grooves 11 and the usual bevelled upper portion 12 for the more ready 90 entrance of the bobbin holding rings into the grooves of the bobbin holding jaws.

Where the shank portion of the bobbin holder is bent, as hereinbefore described, it is preferred that a filler piece be inserted between the side portions of the shank to maintain the side portions of the shank in proper supported relation, and as shown in the present instance, the filler 13 extends frontwardly and has an inclined portion 14 which extends between the bobbin holding jaws into position to engage the under side of the bobbin guide, as will appear.

The bobbin guide comprises the top plate 15 and bottom plate 16 between which extends the inclined bobbin guiding portion 105

17, and the bottom plate 16 is preferably widened (as at 18) to provide a rest for the lower edges of the bobbin holding jaws.

In assembling the parts, the shank 7 of the bobbin holder is seated within the shank receiving chamber 3 of the shuttle, the curved outer surface of the bend at 8 resting against the wall 19 of the shuttle body formed at the end of the shank receiving chamber. Where the shank portion is provided with a filler block, as 13, the block may be assembled with the shank prior to its insertion in the shank chamber, or afterward, if preferred. When the bobbin has been assembled in the shuttle as described, the bobbin guide is moved to place, at which time the top plate 15 of the bobbin guide rests upon the top of the shank portion 7 of the bobbin holder, while the under or bottom plate 16 rests against the lower surface of the shank 7.

As will be noted in Fig. 1, the top and bottom plates of the bobbin guide are wider than the like dimension of the shank 7 of the bobbin holder, with the result that the top plate 15 not only rests upon the top of the shank portion 7 but overlies the shoulder 5 formed in the shuttle wood, as hereinbefore described. Similarly, the bottom plate 16 when moved to place, enters the groove 6 formed in the shuttle wood, and consequently, the bottom plate not only rests upon the lower surface of the shank 7, but also is contained within the groove 6 of the shuttle wood.

In order that the parts thus assembled may be rigidly and permanently secured together as a unit, the present invention contemplates a clamping or through bolt 20 which, as shown in Fig. 2, passes through the top plate 15 of the bobbin guide, and through the opening 21 formed at the end of the shank 7, and likewise, the clamping or through bolt 20 passes through the bottom plate 16 of the bobbin guide, and the parts thus assembled are clamped together as a unit by means of a nut 22, the result being that when the nut 22, or similar securing means, is tightened on the threaded end of the bolt, the top plate and bottom plate of the bobbin guide are clamped to the shank 7 of the bobbin holder, without dependence upon the wood of the shuttle for holding the bobbin guide in position as heretofore.

When the filler 13 is employed, the clamping bolt will be passed through the opening 21 formed between the end of the filler and the curved end of the shank 7, as indicated in Figs. 1 and 2.

In order that the clamping bolt 20 may register with the opening in the top and bottom plates of the bobbin guide and the opening through the shank of the bobbin holder when the parts are assembled, the

top and bottom plates may be provided with vertically aligned registering openings 23 and 24, the result being that the top and bottom plates of the bobbin guide and the shank of the bobbin holder are clamped together as a unit by the clamping bolt, and the top and bottom plates also bear upon the wood of the shuttle at the sides of the shank 7, which serves to give stability and insure proper relation of the parts during subsequent weaving.

The shank of the bobbin holder has a transverse opening 25 through which passes the transverse bolt 26, and where the filler 13 is employed, such filler is also held in place by the transverse bolt 26.

The shank portion 7 of the bobbin holder from the point 8 to the outward flaring bend of the bobbin holding jaws, is much longer than usual, with the result that the shank has increased bearing in the wood of the shuttle, and a more satisfactory support is afforded for the bobbin holding jaws.

In the modification shown by Fig. 4, the clamping or through bolt 20 for securing together the top and bottom plates of the bobbin guide and the shank of the bobbin holder, is passed through these parts at the opposite side of the transverse bolt 26, and such construction is within contemplation of the present invention, although in most cases the location of the clamping or through bolt at the end of the shank of the bobbin holder is preferred. In either case, however, the through bolt and its clamping means, such as the nut 22, serve to clamp and hold together as a unit the top and bottom plates of the bobbin guide and the shank of the bobbin holder, and where the top and bottom plates of the bobbin guide are wider than the like dimension of the shank of the bobbin holder, the clamping or through bolt serves to draw these parts closely against the shuttle wood.

It will be noted that the nut or bolt clamping means 22 does not bear against the wood of the shuttle in order to clamp the bobbin guide and bobbin holder together, but bears directly against the plate of the bobbin guide, the bottom plate in the illustrated form of the invention, and the wood of the shuttle is cut away to provide a recess for the entrance of the nut 22.

Where the filler 13 is of the type hereinbefore described, and as shown in Fig. 1, the inclined end portion 14 thereof serves as a support for the inclined bobbin guide by engaging its under surface, but such construction may not always be necessary.

What is claimed is:

1. A shuttle having, in combination, a body portion, a bobbin holder comprising a shank portion and spring jaws, a bobbin guide having a top plate and a bottom plate resting against the top and bottom of the

said shank portion, a through bolt which passes through the top and bottom plates of the bobbin guide and through the shank portion of the bobbin holding jaws, the head 6 of said bolt bearing upon one of said plates and securing means on the opposite end of the bolt bearing directly upon the other of said means for directly clamping said metal parts together as a unit without dependence 10 upon the wood of the shuttle.

2. A shuttle having, in combination, a body portion, a bobbin holder comprising a shank portion bent to form spring jaws, a bobbin guide having a top and bottom plate 15 embracing the shank portion of the bobbin holder, a through bolt passing through the top and bottom plates of the guide and through the shank portion of the jaws, the head of the bolt bearing upon one of said 20 plates and a nut on the other end of the bolt bearing directly upon the other of said plates for directly clamping the metal parts together as a unit.

3. A shuttle having, in combination, a body portion, a bobbin holder comprising a shank bent to form bobbin holding jaws, a bobbin guide having a top and a bottom plate inclosing said shank, a through bolt 25 which passes through the top and bottom plates and through the shank of the bobbin holder, the head of the bolt bearing upon one of said plates and securing means for the opposite end of the bolt bearing directly 30 upon the other of said plates for clamping the metal parts together, and a transverse bolt 35 passing through the shank.

4. A shuttle having, in combination, a body portion provided with a shank receiving chamber, a bobbin holder comprising a shank seated in said chamber and bent to 40 form projecting spring jaws, a bobbin guide having a top plate and a bottom plate embracing the shank and overlying the adjacent wood of the shuttle, a clamping bolt 45 passing through the top plate, shank, and bottom plate, the head of the bolt bearing upon one of said plates and a nut on the other end of the bolt bearing directly upon the other of said plates for clamping said 50 parts together and the top and bottom plates to the shuttle wood.

5. A shuttle having, in combination, a

body portion, a bobbin holder comprising a shank portion bent to form spring jaws, a filler block in the shank portion forming 55 with the bend of the shank a through bolt opening at the bend of the shank, a bobbin guide having a top plate and a bottom plate seated on the shank, and a clamping bolt passing through the top plate, the bolt opening at the end of the shank, and the bottom plate and having a head bearing upon one of said plates and a nut at its opposite end bearing directly upon the other of said plates for clamping said parts together. 60

6. A shuttle having, in combination, a body portion provided with a shank receiving chamber, a bobbin holder comprising a shank seated in said chamber and bent to 65 form projecting spring jaws, a bobbin guide 70 having a top plate and a bottom plate embracing the shank and overlying the adjacent wood of the shuttle, a clamping bolt passing through the top plate, shank, and bottom plate for clamping said parts together and the top and bottom plates to the shuttle wood, and a transverse bolt passing through the shank and holding the parts to 75 the shuttle.

7. An automatically threading loom shuttle, having a shank receiving chamber, a bobbin holder comprising a shank and bobbin holding jaws, said shank having a through bolt opening at its closed end and a vertical through bolt extending through 85 said opening and bearing upon the closed end of the shank to prevent endwise displacement of the bobbin holder in the shank receiving chamber.

8. An automatically threading loom shuttle, having a shank receiving chamber, a bobbin holder comprising a shank and bobbin holding jaws, said shank having a through bolt opening at its closed end, and a vertical through bolt extending through 95 said opening and bearing upon the closed end of the shank to prevent endwise displacement of the bobbin holder in the shank receiving chamber.

In testimony whereof, we have signed our 100 names to this specification.

WALLACE I. STIMPSON.
HARRY A. DAVIS.
